UNITED STATES PATENT OFFICE.

JOHN O. MOORE AND JOHN IRA JOHNSON, OF CULVERTON, GEORGIA.

CRATE-BODY FOR WAGONS.

No. 855,721.

Specification of Letters Patent.

Patented June 4, 1907.

Application filed July 5, 1906. Serial No. 324,815.

To all whom it may concern:

Be it known that we, JOHN O. MOORE and JOHN IRA JOHNSON, citizens of the United States, both residing at Culverton, in the 5 county of Hancock and State of Georgia, have invented certain new and useful Improvements in Crate-Bodies for Wagons; and we do hereby declare the following to be a full, clear, and exact description of the same, 10 reference being had to the accompanying drawings, forming a part of this specification, and to the figures and letters of reference marked thereon.

The object of this invention is to provide a 15 crate for use on wagons and vehicles and particularly designed for carrying baskets of fruit from the orchard to the shipping place or market, as the case may be, without danger of injuring the contents of the baskets either 20 in quality or appearance.

A further object of the invention is to provide a wagon crate which may itself be shipped from the factory in knock down form and easily set up by the purchaser or 25 user without the employment of special fittings or tools and when so set up will possess the strength and rigidity of a wagon body but having a greater capacity.

The invention consists in certain novel details of construction and combinations and arrangements of parts all as will be herein-after described and pointed out particularly in the appended claims.

Referring to the accompanying drawings— 30 Figure 1 is a perspective view of a crate embodying the present improvements, the doors in the partition or intermediate deck being shown open in dotted lines. Fig. 2 is a section taken in the vertical plane transversely 40 of the crate. Fig. 3 is an end elevation and Fig. 4 a side elevation of the same.

Like letters of reference in the several figures indicate the same parts.

The bottom or carry log of the crate, which 45 corresponds to a bottom of the wagon body, and in fact, which may be formed by the ordinary platform at present used in some instances on a wagon running gear, is indicated by the letter A in the accompanying drawings, and it will be understood that when this portion of the crate constitutes a part to be manufactured and sold with the crate, it is made of a size to fit the running gear of the wagons on which the crate is to be used. 50 Thus it is intended that in manufacturing the crates the bottoms or carry logs shall be

made of a width and length to fit standard running gears and for either one or two horse wagons.

At each side, the bottom or carry log is 60 provided with stake straps or irons B adapted for the reception of lower ends of upwardly extending stakes C preferably three or four in number on each side, said stakes being united to and forming an integral part 65 of the sides of the crate. The other members of the sides of the crate, consist of longitudinal strips D, preferably three in number, and spaced somewhat widely, the bottom and top strips being preferably de- 70 signed to form a bearer against which the lower portions of the baskets carried by the crate will contact to hold the baskets in position. The front and rear ends of the crate are formed of vertical strips D' correspond- 75 ing to the stakes B, save that they do not extend below the top of the carry log and said vertical strips D' are connected to and form an integral structure with the horizontal strips E which correspond in location and 80 function with the strips C forming the sides of the crate. The ends of the crate formed as thus described, are preferably confined between the sides, but are held in place by clips or straps F passing around the corners 85 of the crate at top and bottom as shown clearly in Fig. 1 and united to the verticals by separable fastenings such as the screws or bolts illustrated. Inasmuch as the stakes at the side should be located a short distance 90 from the ends of the horizontal strips, it is desirable that filling pieces G be employed beneath the clips or corner straps both for the sake of strength and appearance as well as to afford a solid rigid corner at those portions of the crate most liable to injury by 95 contact with other objects.

An intermediate partition or deck is located in the crate at a sufficient height there-in to accommodate one tier of baskets of 100 fruit below the same and to itself constitute a support for the second or upper tier of baskets of fruit. Said partition or intermediate deck is provided with upwardly opening doors or grates which will permit of the placing or removal of the lower tier of baskets to facilitate the loading and unloading of the 105 crate.

In the preferred construction, the partition or deck is preferably formed of cross 110 pieces or supporting timbers H adapted to rest at their ends on the intermediate hori-

5 horizontal strips of the sides of the crate, such cross pieces or timbers being located in the transverse plane of the stakes whereby the weight will be transmitted directly to said stakes and thence to the carry log and running gear. The transverse timbers or supports H are connected adjacent their ends by longitudinal strips I, preferably one at each side of the crate, and the doors or grates K 10 are hinged to the said longitudinal strips I in position to turn up toward the sides of the crate as shown by the dotted lines in Figs. 1 and 2, or to rest when in horizontal position on the timbers H. In this preferred construction, and in order to afford additional strength and rigidity, the partition or deck is provided with down turned hooks or L-irons M adapted to fit into clips or strap irons M' secured to the vertical stakes of the sides of 20 the crate. The connection thus formed, while it will permit of the partition being moved vertically, prevents any spreading of the sides of the crate and well adapts the same for use in handling loads liable to shift or 25 spread transversely.

In manufacturing crates in accordance with this invention, it is designed that the sides, ends and partition or deck shall be completed separately and shipped knocked down with the several parts bound together in a flat package. The purchaser or user is required to secure the corners together by the corner straps or clips and to mount the same in position on a running gear in order to 35 make the device completely available.

In use, the lower tier of baskets is first placed in position, the doors or grates closed down over the same and then the upper tier of baskets is placed upon the partition formed 40 in part by the said doors or grates. It will be noted that by the use of the intermediate partition or deck, the tiers of baskets are kept completely separate and hence there is no danger or liability of the fruit being injured either in quality or appearance by the 45 contact therewith of other baskets.

Where the carry log or bottom is not made and sold as a portion of the crate, it is obvious that the purchaser or user of the crate 50 will have to see that the stake irons are properly positioned to receive the lower ends of

the stakes, although it is designed that the crates shall be made with the stakes in proper position to fit standard arrangements of carry irons and hence no adjustment of 55 said carry irons will ordinarily be found to be necessary.

By the use of the partition, the capacity of a wagon as now used is practically doubled, and at the same time, provision is made 60 whereby when necessary, the said partition or deck may be removed and the crate then used for handling ordinary farm produce in barrels or loose as the case may be.

Having thus described our invention, what 65 we claim as new and desire to secure Letters Patent thereon, is:—

1. In a wagon crate, the combination with the sides formed of vertical stakes adapted to enter stake irons at their lower ends and horizontal strips rigidly connecting said stakes, ends formed of vertical supports and horizontal strips rigidly connected thereto and clips connecting said sides and ends at the corners to form a rectangular body, of a 75 horizontal partition or deck mounted in said crate and removably connected to the verticals at an intermediate point, said deck embodying in its construction a central cross piece adapted to rest at its ends on the intermediate horizontal strip of the sides and having upwardly opening doors adapted when closed to be supported intermediate their ends by said central cross piece.

2. In a wagon crate, the combination with 85 the sides and ends formed respectively of verticals supporting horizontal strips, said sides and ends being connected together at the corners, of a horizontal partition mounted in 90 said crate at an intermediate point and connected with the sides of the crate by hook like connections, whereby the spreading of the sides of the crate is prevented and doors extending from end to end of said partition and adapted to open outwardly to permit of 95 access to the lower portion of the crate; substantially as described.

JOHN O. MOORE.

JOHN IRA JOHNSON.
